DESIGN FOR A JUMPER DRESS

Joset Walker, New York, N. Y.

Application July 31, 1943, Serial No. 110,816

Term of patent 3½ years

To all whom it may concern:

Be it known that I, Joset Walker, a citizen of the United States, residing in New York city, in the county of New York and State of New York, have invented a new, original, and ornamental Design for a Jumper Dress, of which the following is a specification, reference being had to the accompanying drawing, forming part thereof.

Fig. 1 is a front view of a jumper dress showing my design.

Fig. 2 is the rear view of the jumper dress shown in Fig. 1.

I claim:

The ornamental design for a jumper dress, substantially as shown.

JOSET WALKER.
